United States Patent Office

Des. 220,819
Patented May 25, 1971

220,819

LUGGAGE HANDLE

Joseph N. Laurita, 66—19 Clinton Ave.,
Maspeth, N.Y. 11378

Filed May 18, 1970, Ser. No. 23,046

Term of patent 14 years

Int. Cl. D8—03

U.S. Cl. D8—154

FIG. 1 is a front perspective view of a luggage handle showing my new design;

FIG. 2 is a top plan view thereof;

FIG. 3 is a side elevational view thereof;

FIG. 4 is an end view thereof; and

FIG. 5 is a bottom plan view thereof.

I claim:

The ornamental design for a luggage handle, as shown.
